UNITED STATES PATENT OFFICE

WILLIAM PRINCE-SMITH AND DAVID WATERHOUSE, OF KEIGHLEY, ENGLAND

MEANS FOR FACILITATING DOFFING IN FLYER SPINNING, TWISTING, AND SIMILAR MACHINES

Application filed November 8, 1930, Serial No. 494,424, and in Great Britain December 7, 1929.

This invention relates to flyer spinning, twisting, and similar machines provided with mechanical doffing apparatus and of the type having means for the purpose of aligning the flyers in a plane parallel with the machine prior to the doffing operation, and having also a series of angularly movable prongs adapted to control the threads during the manipulation of the full bobbins when doffing; the invention having for its objects to secure a better control of the threads during doffing, and to facilitate and expedite the doffing operation.

Accordingly, a flyer spinning, twisting or similar machine of the type referred to is provided, in rear of the flyers, with a series of angularly movable wipers or prongs adapted to engage and retain the threads and to function in association with thread severing means as well as with thread guiding and controlling means to cause the severed threads to be correctly wrapped on the empty bobbins when exchanged for the full bobbins by appropriate bobbin manipulating mechanism.

The aforesaid wipers or prongs may consist of pairs of hook-ended rigid wires carried by an angularly movable rod, the hooked ends of each pair being capable of entering between the legs of the correspondingly opposite flyer; and upon each wire there may be mounted slidably a weight or equivalent member adapted to be displaced by gravity or otherwise suitably whereby to trap and nip a thread in the appropriate hooked end wherein it may be caught when said wipers or prongs are moved angularly through the flyers at a particular stage of the doffing operation.

40 The thread-severing means, across which said wipers or prongs are adapted to lay the threads, may be of any convenient form, and, after said thread-severing means have been caused to operate, the severed ends of the threads are nipped by said wipers or prongs while the aforesaid thread guiding and controlling means are operated.

The guiding and controlling of the severed ends of the threads may be accomplished by 45 means of a continuous horizontal rail located

between the aforesaid angularly movable rod and the flyers, in conjunction with which a vertically movable horizontal continuous rod is adapted to be operated in such manner as to bear upon the severed threads behind and adjacent to those flyer eyes through which they pass while the empty bobbins are being positioned relatively to the flyers and to put tension in and so ensure that the loose ends of the severed threads are correctly laid on to said empty bobbins when the frame is restarted; the aforesaid slidably mounted weights serving to produce the correct tension in the threads to enable the proper laying-on to be effected, and the aforesaid horizontal rail and vertically movable horizontal rod serving to dispose of the loose ends once the thread has become attached to each empty bobbin.

The invention is illustrated, by way of example, in the accompanying drawings, in which Figures 1, 2, 3 and 4 are vertical sections, showing the respective positions occupied by the parts throughout the doffing operation. Figure 5 is a plan view and Figure 6 is a front elevation of a wiper or thread-retaining means.

In these figures the general constructional features of the machine are already known and therefore do not require specific description, in fact structurally the machine resembles closely that described in specification of United States Patent No. 1,543,618.

Figure 1 shows the position of all the parts during spinning, a series of bobbins having just become filled with the correct amount of thread.

The flyers are first of all positioned, as seen in Figure 2, in a plane parallel with the machine. The full bobbins are then lowered on to the appropriate transfer rail the pegs on which have been aligned below the spindles, in the manner described in United States specification No. 1,543,618, in which position the threads will stretch vertically from the flyer eyes to the full bobbins and some may also have become wrapped more or less round the spindles.

50 *a* are the spindles, upon which are secured the flyers *b* in the usual manner, and *c* and

d are the full and empty bobbins respectively, while *e* is a longitudinally slideable rod carrying forwardly projecting pins *f* adapted to contact with and straighten the flyers *b*, *g* is the fixed overhead rail in which the flyers *b* are supported in the known way.

h is the pinion shaft for raising and lowering the rail *C*, and *j* is the pinion shaft for moving the rack bars *k* horizontally towards 10 and from the spindles; said rack bars *k* supporting cranked brackets *l* supporting two rows of transfer pegs *m*, *m'*, projecting vertically upwards from peg rails *n*, *n'*, carried by said cranked brackets *l*.

15 All said parts are known as to their construction and operation.

o is a rod arranged longitudinally of the machine, in suitable bearings, in rear of the spindles and capable of being moved angularly by means of a hand-piece or hand-wheel (not shown).

Behind each spindle *a* a boss or sleeve *o'* is secured by a set screw *o*² upon the rod *o* and each boss or sleeve *o'* is formed integrally 25 with a rearwardly projecting arm *o*³ in which is mounted a pair of hook-ended, rigid wires *p*, *p*, whereof the inner ends are screw-threaded and are secured by clamping nuts *p'*, *p'*, in the arm *o*³.

30 The forward ends of said wires *p*, *p*, are hook-shaped, as at *p*², *p*², and each pair of wires *p*, *p*, is so spaced as to be capable of entering between the legs of the correspondingly opposite flyer *b*.

35 Upon each wire *p* a weight *p*³ is mounted slideably.

q, *q'*, *q*² is a thread cutter bar of known form, and *r* is a continuous rod which is supported on the rail *C*, by a number of upstanding slotted brackets *r'*.

s is a continuous rail attached to and carried by a forwardly extending arm *s'* formed integrally with each boss or sleeve *o'* mounted on the angularly movable rod *o*.

45 After the bobbins *c* have been filled with the required amount of thread, the parts being as positioned in Figure 1, the flyers *b* are straightened by rod *e* and pins *f*, the rail *C*, is then lowered, by turning pinion shaft *h*, 50 and when rail *C* reaches its lowermost position, as in Figure 2, the pinion shaft *j* is rotated to cause the rack bars *k* to position the cranked brackets *l* so that the transfer pegs *m* are axially below the spindles *a*.

55 The pokers *E*¹ and lifter rail *D* are then lowered until the full bobbins *c* are passed over the transfer pegs *m* and rest on the transfer rail *n*. The threads *T* will then stretch vertically from the eye of each flyer 60 to each full bobbin *c* and some may perhaps also be wrapped slightly round some of the spindles *a*.

The next operation is to move the rod *o* angularly in a counter-clockwise direction 65 through 360 degrees so that the hook-ended

wires or wipers *p* sweep through the legs of all the flyers *b*.

As the wipers *p* move upwards the slideable weights *p*³ fall by gravity away from the hooks *p*² leaving the latter free, as they pass 70 between the flyer legs, to catch the threads *T* which are then carried by the wipers *p* across the cutter bar *q*, and as the wipers *p* re-assume their vertically downwards position the weights *p*³ slide down to the hooks *p*² and nip 75 the threads therein. The path of the thread *T* at this stage is clearly seen in Figure 2.

The threads are then severed by operating the cutter mechanism *q*, *q'*, *q*², which leaves 80 the threads as shown in Figure 3, that is to say, with each severed end of thread held by a weight *p*³ on one or other limb *p* of each wiper; and the empty bobbins *d* are then aligned below the spindles *a* by means of pinion shaft *j* and rack bars *k* also as shown in 85 Figure 4.

The lifter rail *D* is now caused to position the empty bobbins *d* on the spindles *a*, and at the same time rod *r* is elevated into the position shown in Figure 4 and is brought into contact with the rail *s* (which is stationary at this stage) for the purpose of tensioning the threads after leaving the hooked ends of the wipers. The cranked brackets *l* are moved 90 outwards to the full extent and the flyer straighteners *e* and *f* are withdrawn whereupon the machine is ready for re-starting.

As soon as the flyers start rotating the threads are under tension between the flyer eyes and the weights *p*³, which, as the threads 100 slip away from under the weights, causes the threads to wrap around the empty bobbins, the contacting rod *r* and rail *s* putting tension upon and so ensuring that the loose ends are correctly disposed of.

105 The threads are therefore cleared from the spindles, caught and held in tension whilst they are being severed, the severed ends of the threads being subsequently held in tension, causing the flyers to start wrapping 110 thread on to the empty bobbins. The severed threads are guided correctly on to the empty bobbins and at the same time held in tension which ensures that the loose ends are disposed of correctly by being wrapped on to the 115 bobbin, the threads being severed whilst the machine is stationary, with the result that a superior control of the thread is obtained, loose ends disposed of, and doffing is simplified and expedited.

120 What we claim is:—

1. In a flyer-spinning, twisting and similar machine provided with mechanical doffing apparatus, spindles, flyers mounted on said spindles, bobbins on said spindles, threads 125 passing through said flyers and wound on said bobbins on said spindles, transfer pegs, empty bobbins on some of said transfer pegs, thread severing means, a series of angularly movable members located in rear of said spindles, 130

means to move said angularly movable members into the paths if said threads extending from said flyers to said bobbins on said spindles, means carried by said angularly movable members to seize said threads when said bobbins have been transferred by said mechanical doffing apparatus to some of said transfer pegs, said means on said angularly movable members also serving to retain the ends of said threads passing through said flyers after severance by said thread severing means, and means to tension said ends of said threads upon their release from said retaining means on said angularly movable members.

15. 2. In a flyer-spinning, twisting and similar machine provided with mechanical doffing apparatus, spindles, flyers mounted on said spindles, bobbins on said spindles, threads passing through said flyers and wound on said bobbins on said spindles, transfer pegs, empty bobbins on some of said transfer pegs, thread severing means, a series of angularly movable members located in rear of said spindles, said angularly movable members 25 consisting of pairs of hook-ended rigid wires, means to move said angularly movable members into the paths of said threads extending from said flyers to said bobbins on said spindles, means carried by said angularly movable members to seize said threads when said bobbins have been transferred by said mechanical doffing apparatus to some of said transfer pegs, said means on said angularly movable members also serving to retain the ends of said threads passing through said flyers after severance by said thread severing means, and means to tension said ends of said threads upon their release from said retaining means on said angularly movable members.

40. 3. In a flyer-spinning, twisting and similar machine provided with mechanical doffing apparatus, spindles, flyers mounted on said spindles, bobbins on said spindles, threads passing through said flyers and wound on said bobbins on said spindles, transfer pegs, empty bobbins on some of said transfer pegs, thread severing means, a series of angularly movable members located in rear of said spindles, said angularly movable members consisting of pairs of hook-ended rigid wires, means to move said angularly movable members into the paths of said threads extending from said flyers to said bobbins on said spindles, members carried slidably by said angularly movable members to seize said threads when said bobbins have been transferred by said mechanical doffing apparatus to some of said transfer pegs, said means on said angularly movable members also serving to retain the ends of said threads passing through said flyers after severance by said thread severing means, and means to tension said ends of said threads upon their release from said retain-

ing means on said angularly movable members.

4. In a flyer-spinning, twisting and similar machine provided with mechanical doffing apparatus, spindles, flyers mounted on said spindles, bobbins on said spindles, threads passing through said flyers and wound on said bobbins on said spindles, transfer pegs, empty bobbins on some of said transfer pegs, thread severing means, a series of angularly movable members located in rear of said spindles, said angularly movable members consisting of pairs of hook-ended rigid wires, means to move said angularly movable members into the paths of said threads extending from said flyers to said bobbins on said spindles, gravity operated members carried slidably by said angularly movable members to seize said threads when said bobbins have been transferred by said mechanical doffing apparatus to some of said transfer pegs, said means on said angularly movable members also serving to retain the ends of said threads passing through said flyers after severance by said thread severing means, and means to tension said ends of said threads upon their release from said retaining means on said angularly movable members.

5. In a flyer-spinning, twisting and similar machine provided with mechanical doffing mechanism and having spindles carrying flyers, a pair of angularly movable hook-ended rigid wires located in rear of each of said spindles, a gravity-operated sliding weight upon each of said wires, and means to move said wires angularly towards said spindles.

In testimony whereof they affix their signatures.

WILLIAM PRINCE-SMITH.
